UNITED STATES PATENT OFFICE.

DENNIS DUNN, OF MAHANOY CITY, PENNSYLVANIA, ASSIGNOR OF ONE-HALF TO THOMAS GORMAN, OF SAME PLACE.

AIR-BRAKE FOR RAILWAY-CARS.

SPECIFICATION forming part of Letters Patent No. 431,938, dated July 8, 1890.

Application filed May 12, 1890. Serial No. 351,493. (No model.)

To all whom it may concern:

Be it known that I, DENNIS DUNN, a citizen of the United States, and a resident of Mahanoy City, in the county of Schuylkill and State 5 of Pennsylvania, have invented certain new and useful Improvements in Air-Brakes for Railway-Cars; and I do hereby declare that the following is a full, clear, and exact description of the invention, which will enable 10 others skilled in the art to which it appertains to make and use the same, reference being had to the accompanying drawings, which form a part of this specification.

My invention relates to improvements in 15 air-brakes for railroad and other cars, the object being to provide simple and effective means for compressing the air and supplying it to the brake mechanism.

The invention consists in the novel construction and combination of parts herein-after fully described, and definitely pointed out in the claims.

In the accompanying drawings, Figure 1 represents a side elevation of my improved 20 compressing and braking device applied to a car. Fig. 2 is a plan view of the same. Fig. 3 is a detail sectional view of the air-reservoir and liquid-receptacle. Fig. 4 is a similar view of the air-compressor. Fig. 5 is a 25 detail view of the three-way cock.

In the said drawings, the reference-numeral 1 designates the platform of a car, and 2 the wheels.

Secured to the axle 3 of one pair of wheels 35 is a cog-wheel 4, which meshes with a similar wheel 5, mounted in brackets 6, depending from the bottom of the car.

7 designates the air-compressor bolted or otherwise connected with the car-bottom. It 40 consists of a cylinder 8, within which works a piston 9, connected by means of piston-rod 10 and connecting-rod 12 and crank-pin 13 with the cog-wheel 5.

At each end of the cylinder 8 are secured 45 the entrance and exit pipes 14 and 15, the pipe 14 being open to the air, and pipe 15 connecting by pipe 16 with the reservoir 17. In each of these pipes 14 and 15 are located check-valves 18 18^a 18^b 18^c, which are so arranged that while one is open the other is closed—that is to say, when the piston is

traveling in the cylinder in the direction indicated by the arrow valves 18^a and 18^b will be closed and valves 18 and 18^c will be open. The air compressed in the cylinder will then 55 escape through valve 18^c and be conducted to reservoir 17 by means of pipe 16. A safety-valve should be connected with pipe 16, so that when the pressure shall have reached a certain point it will open and allow the air to 60 escape, as will be understood by those skilled in the art. This air-reservoir is secured to the car in any convenient manner and communicates by means of pipe 19 with a liquid vessel or receptacle 20, containing glycerine 65 or other suitable liquid, which is forced by the compressed air to the piston-cylinder which operates the brake, as will be herein-after described. Connected with pipe 19 is a three-way cock 21, so constructed and arranged that when turned one way communication will be established between the reservoir 17 and vessel 20, and when turned the other way to shut off communication there-between it will communicate with the atmos- 70 75 phere.

The numeral 22 designates a pipe leading from near the bottom of vessel 20 to the brake-cylinder 23, having piston 24. The piston-rod 25 of piston 24 is connected with 80 rectangular-frame 26, which in turn is connected with rod 27, connected with the pivoted brake-levers 28, carrying the brake-shoes 29. Secured to this frame are springs 30, the tendency of which is to throw the 85 brake-shoe out of contact with the wheels. The cock 21 is connected with a lever or other device by which it may be operated to set the brakes.

The operation is as follows: When the cars 90 are started, the wheels actuate the piston 9 by means of the cog-wheels and connections. This will cause the air to be compressed and stored in the reservoir 17 until wanted for use. The safety-valve will prevent too great 95 a pressure being attained. When in normal condition, the three-way cock will close communication between reservoir 17 and vessel 20. When, however, it is desired to apply the brakes, the cock 21 is turned so as to open 100 communication between reservoir 17 and vessel 20 and cut off communication with the

open air. The compressed air will now rush to vessel 20, and acting upon the liquid contained therein will force said liquid through pipe 22 to the cylinder 23, causing the piston 5 therein to be actuated and the brakes applied through the connections therewith. When it is desired to release the brakes, the three-way cock is operated to shut off communication between reservoir 17 and vessel 20 and 10 open communication from vessel 20 with the open air, when the springs 30 will cause the piston to be operated in a reverse direction and the brake to be retracted.

Having thus described my invention, what 15 I claim is—

1. A mechanism for operating air-brakes, consisting of an air-compressor actuated by the car-axles, a reservoir connected with the air-compressor, a liquid-vessel, a pipe having 20 a three-way cock connecting said reservoir and vessel, a brake-cylinder having piston

connected with the brakes, and a pipe connecting the brake-cylinder and liquid-reservoir, substantially as described.

2. In a mechanism for operating air-brakes, 25 the combination of an air-compressor, a reservoir, a liquid-vessel, a pipe connecting said reservoir and liquid-vessel provided with a three-way cock, a pipe leading from the bottom of said vessel to the brake-cylinder, a 30 piston in the brake-cylinder, a piston-rod connected with a frame for setting the brakes, and springs for retracting the brakes, substantially as described.

In testimony that I claim the foregoing as 35 my own I have hereunto affixed my signature in presence of two witnesses.

DENNIS DUNN.
